(57) **CLAIM**

The ornamental design for a tire, as shown.

DESCRIPTION

FIG. 1 is a perspective view of a tire according to our new design.

FIG. 2 is a front elevational view thereof, the rear, top and bottom views being mirror images; and,

FIG. 3 is a right side elevational view thereof, the opposite side view being a mirror image.

The broken lines form no part of the claimed design.

1 Claim, 3 Drawing Sheets

FIG. 1

FIG. 2

FIG. 3
